PREADDRESSED ENVELOPE FOLDER

Edward T. White, Rockville Centre, N. Y.

Application November 9, 1933, Serial No. 697,330

2 Claims. (Cl. 229—92.5)

The subject-matter of the present invention relates generally to advertising devices and the improvements are directed to a novel form of envelope folder or mailing piece of such a nature as to be of practical value in the use of modern conditions and further to meet all the requirements of the U. S. Postal Laws and Regulations pertaining particularly to the use of mailing permits for the use of first-class and third-class rates.

Primarily, the object of the invention is to provide an article of the above-mentioned character embodying an advertising folder and envelope so arranged to comprise a mailing piece of great value and that can be of practical value in passing through the United States mails, thereby allowing business houses and enterprises to promote the sale of their products.

As will presently appear, it is proposed to provide an article adapted to bear advertising matter, or the like, on its face or rear portion, or both, said article being foldable along a plurality of fold lines to conceal a detachable coupon or business reply postal card and also an envelope adapted to receive said coupon and a remittance in the event the nature of the proposed transaction includes the same.

The invention is further featured by the provisions aforesaid wherein the recipient of the folder returns a pre-addressed envelope containing the detachable coupon and also a remittance without resort to signing or writings of a similar nature.

A further object of the invention is to provide a mailing piece containing the names of the addressee and addressee which can be sent through the mails at third-class postage rates and subject to any required postal inspection.

Still another object of the invention is to produce a folder that incloses a pre-addressed envelope returnable to the sender at first-class postage rates and which at the same time provides a reply postal card that may be sent to the sender as third-class matter.

With these objects in view, together with others which will appear as the description proceeds, the invention resides in the novel formation, combination, and arrangement of parts, all as will be described more fully hereinafter, illustrated in the drawing, and particularly pointed out in the claims.

In said drawing:

Figure 1 is a plan view of the face portion of my improved envelope folder.

Fig. 2 is a similar view of the reverse side thereof.

Fig. 3 is a view of the front of the envelope to be sent with said folder.

Fig. 4 is a view of the rear of said envelope.

Fig. 5 is a perspective view showing the article in partial folded condition.

Fig. 6 is a view of the article completely folded and ready for mailing.

Fig. 7 is an end view, somewhat diagrammatic, illustrating the general arrangement of the parts when the article is in the condition shown in Fig. 6.

Referring now more in detail to the accompanying drawing, wherein like characters of reference denote similar parts throughout the several views, let 5 indicate generally the folder 15 shown in Figs. 1 and 2, wherein it will be noted the body portion thereof preferably comprises end section 6, intermediate section 7 and top section 8, said sections being foldable on score lines 9 and 10, as will presently appear. Extending from said top section 8 is another section 11 which may serve as a coupon or a business reply postal card according to the desires of the advertiser. Another score line 12 separates said section 8 and section 11 and permits folding of the sections and 25 which may also serve to permit the severance of said coupon or postal card from the other sections comprising the folder.

Upon inspection of Fig. 1 it will be noted that section 6 is provided with a tongue 13 and an elongated opening 14, the former being insertable in a slot 15 in section 7, while the latter exposes the name and address of the party receiving the article. As shown in Fig. 2, sections 7 and 8 may be provided with printed matter 16 and 17, which may be in the nature of advertising or any other matter to be brought to the attention of the receiver of the mailing piece, whilst section 11 is provided with printed matter 18 responsive to said printed matter 16, said section further bearing the name of the sender of the folder, as shown at 19, and the name and address of the recipient, as shown at 20. Said section 6 may be provided with printed matter 21, (see Fig. 2), serving as instructions in the use of the folder, and as shown in Fig. 1, the name of the sender appears at 22 on section 6, whilst the section 11 is also provided with the name and address of the sender 23 and printed to show that no postage is required or other printing matter conforming to the postal rules and regulations.

As pointed out hereinbefore, it is proposed to include an envelope with the folder, said envelope 24 bearing the name and address of the party to receive said envelope, as shown at 25, 55

Fig. 3 and being also printed to show that no return postage is required or other forms conforming to the postal laws. The rear face of said envelope, (see Fig. 4) is provided with the printed name and address 26 of the party returning the envelope 24. It will be noted that said envelope 24 is provided with the usual flap 27, gummed at 28 so that inclosures in the nature of remittances, or the like, may be sealed within said envelope and the latter returned as first-class postage.

The foregoing briefly describes the essential parts and elements of the folder, whose cooperation and functioning will become apparent as the use and operation of the device is described below.

As pointed out hereinbefore, the folder may be used as an advertising medium containing a return postal card that may be detached and returned to the sender without affixing postage stamps or requiring handwriting of any kind. It has also been explained that the folder may contain an envelope, pre-addressed, and which may be removed from the folder to receive a remittance and a detachable coupon, said envelope then being returnable to the sender without postage or handwriting. In the first instance, section 11 is a business reply postal card, and in the second instance, said section is in the nature of a coupon.

When the section 11 is to be used as a pre-addressed postal card, the other sections are folded on the score lines, and as shown in Fig. 5, section 8 is folded on line 10 to overlie section 7, whilst section 11, is folded on line 12 to rest over section 8. Section 6 is then folded on line 9 to rest on section 11 and after the tongue 13 has been inserted in slot 15, of section 7, the device has been completely folded, and is now in the condition shown in Fig. 6, wherein it will be noted that the name and address of the party to receive the folder is exposed through the opening 14 of section 6, whilst the name and address of the sender appears in the upper left-hand corner of section 6. The folder in the aforesaid condition is mailable as third-class matter and the postage stamp may be affixed in the upper right-hand corner of section 6, or said stamp may be applied over the exposed portion of said tongue 13.

When the folder has been received and the party receiving the same desires to take advantage of the inducement conveyed by the printed matter, the section 11 is detached from section 8 by tearing on the line 12 and said section 11 is now mailed without the necessity of affixing stamps or resorting to handwriting of any kind. As pointed out hereinbefore, said section 11 is printed on one side with the name and address of the party to receive said section after it has been detached from the folder, and on the reverse side, (see Fig. 2), said section 11 is provided with names and addresses of the addressor and addressee and also printed matter 18 showing an acceptance of the offer contained in said folder.

When said section 11 is to be used as a coupon, the device is folded on the fold lines as indicated above, but before the section 6 is folded, the envelope 24 is placed against the face of said section 11 and the flap 27 is bent over the upper edge of said section. The envelope 24 is so arranged that the name and address 26, (see Fig. 4) is exposed through the opening 14 of section 6 when the latter is folded on the line 9 and its tongue 13 is affixed in the slot 15, as aforesaid. The name and address 26 is positioned on the rear face of the envelope so that the word "From"

is concealed when the section 6 is folded. Thus only the said name and address 26 appears through opening 14. The folder in its present condition may be sent through the mails as third-class matter, said folder being closed at the top but being subject to inspection either by pulling the inclosed envelope out sideways or by lifting the tongue and extracting the envelope entirely.

The party receiving the folder may detach the coupon 11 and place it within the envelope 24 along with a remittance, whereupon the envelope may be sealed and returned to the sender. In this instance the envelope travels as first-class matter, but the sender is not required to affix postage or to resort to any handwriting.

From the foregoing it will be seen that my improved folder may serve as an advertising medium or as a medium of conducting business transactions. The folder can be sent as third-class matter and the reply postal card does not require postage or any writing thereon. In other words the folder and its postal card are pre-addressed, and the receiver may optionally return the postal card as third-class matter or he may return the envelope as first-class mail matter. The folder and its contents can be readily and conveniently inspected, and further the folder may be made in various sizes and weights as the contained envelope gives body to the folder thereby enabling the user to save money by using cheaper paper. The prospect or advertiser using the folders also saves money by having to use only one envelope instead of two, and a further saving is effected by dispensing with the use of stickers. The field of the use of the folder is practically unlimited in that the same may be used in connection with subscriptions and renewals, coupons, questionnaires, contracts, letterheads, statements, bills, purchase orders and in other transactions where a reply by mail is requested or can be made.

While the foregoing presents the invention in its preferred form, it will be understood that changes within the scope of the claims may be resorted to without departing from the spirit of the invention.

I claim:

1. An article of the class described comprising an end section having a tongue portion and an elongated opening, an intermediate section having a slot to receive said tongue, a top section, said sections being bounded by parallel score lines, a detachable section extending from said top section, said top section being foldable upon said intermediate section and said detachable section being foldable upon the latter in a reverse direction and said end section being foldable upon said detachable section, and an envelope removably carried by said detachable section, said envelope being provided with the name and address of the recipient arranged to be exposed through the opening in said end section when the latter is folded onto said envelope and secured in position by means of said tongue and said slot.

2. An article of the class described comprising an end section having a tongue portion and an elongated opening, an intermediate section having a slot to receive said tongue, a top section, said sections being bounded by parallel score lines, a detachable section extending from said top section, said top section being foldable upon said intermediate section and said detachable section being foldable upon the latter in a reverse direction and said end section being foldable upon

said detachable section, and an envelope positioned on the face of said detachable section and having its flap reversely folded to be positioned between said detachable section and said top sec-

5 tion, said envelope being provided with the name and address of the recipient arranged to be ex-

posed through the opening in said end section when the latter is folded onto said envelope and secured in position by means of said tongue and said slot.

EDWARD T. WHITE. 5
